UNITED STATES PATENT OFFICE.

CLEMENS B. WILLENBORG, OF DYERSVILLE, IOWA.

CARRIER.

940,768.

Specification of Letters Patent. Patented Nov. 23, 1909.

Application filed April 12, 1909. Serial No. 489,417.

To all whom it may concern:

Be it known that I, CLEMENS B. WILLENBORG, a citizen of the United States, residing at Dyersville, in the county of Dubuque and 5 State of Iowa, have invented a new and useful Carrier, of which the following is a specification.

This invention has relation to carriers and it consists in the novel construction and arrangement of its parts as hereinafter shown and described.

The object of the invention is to provide a carrier adapted to travel upon a suspended or overhead cable and which is so mounted 15 upon its supporting wheels that the liability of disconnecting the carrier from the supporting cable when the said carrier is given a sudden push is reduced to a minimum.

With the above objects in view the carrier 20 includes a bucket pivotally attached to the end of a bail. One wheel is freely castered to the upper portion of the bail and another supporting wheel is castered for limited movement with relation to the bail and is 25 journaled upon an arm pivoted for vertical swing.

In the accompanying drawings; Figure 1 is a side elevation of the carrier. Fig. 2 is an end elevation of the same showing the 30 bucket in dumping position. Fig. 3 is a vertical sectional view of a portion of the carrier cut on the line 3—3 of Fig. 1. Fig. 4 is a vertical sectional view of a portion of the carrier cut on the line 4—4 of Fig. 1. 35 Fig. 5 is a horizontal sectional view of a portion of the carrier cut on the line 5—5 of Fig. 3.

The carrier consists of a bucket 1 which is pivoted at each end to the extremities of a 40 U shaped bail 2. A disk 3 is mounted upon one end of the bucket 1 and is provided on its periphery with a slot 4. A pin 5 is located upon the outer face of the disk 3 and the lower portion of the adjacent end of the bail 45 2 is in the path of movement of the pin 5 when the bucket assumes a dumping position.

As illustrated in Fig. 2 of the drawings, one end of the bail 2 may be provided with 50 a perforation 6 which at times is adapted to register with a perforation 7 provided in the disk 3. When the said perforations are in alignment with each other the bucket 1 is in receiving position and by inserting a pin or 55 cable securing device (not shown) through the perforations 6 and 7 the said bucket 1

may be held in positive or fixed relation to the bail 2. Guides 8 are carried by one end of the bail 2 and a rod 9 is slidably mounted in the said guides. The rod 9 carries at its lower end a pawl or pin which is adapted to enter the slot 4 provided in the periphery of the disk 3 and hold the bucket 1 in fixed relation with the said bail. A coil spring 11 surrounds the rod 9 and bears at one end against the upper guide 8 and at its lower end against a collar 12 fixed to the said rod 9. The spring 11 is under tension with a tendency to hold the rod 9 in a depressed position in the guides 8. A yoke 13 is pivotally connected with the upper end of the rod 9 and projects beyond the upper intermediate portion of the bail 2.

A lever 14 is positioned upon the upper intermediate portion of the bail 2 and its 75 working end is pivotally connected with the upper end of the yoke 13. The bail 14 lies under a supporting cable 15 which is held suspended by any suitable means. A wheeled frame 16 is pivoted to the upper intermediate portion of the bail 2 and carries a grooved wheel 17 and hence the said wheel is referred to as being freely castered. The 80 said wheel 17 is adapted to travel upon the cable 15. A frame 18 is pivoted for limited 85 pivotal movement at the upper intermediate portion of the bail 2 and an arm 19 is pivoted in the frame 18 and is confined to a limited vertical swinging movement. A grooved wheel 20 is journaled at the forward end of 90 the arm 19 and is also adapted to travel upon the cable 15. Therefore the arm 19 and wheel 20 constitute a caster structure having limited castered movement. The 95 arm 19 is pivoted upon a pin 21 which extends transversely across the frame 18 and the said arm and the vertical swinging movement of the said arm is limited by a cross pin 22 which extends transversely across the frame 18 and lies below the pin 21 in the path of movement of the opposite end portion of the arm 19 from that end thereof to which the wheel 20 is journaled.

Any suitable means may be employed for 105 limiting the castered movement of the frame 18 and as illustrated in Figs. 3 and 5 of the drawings such means consists of a pin 23 which is secured at its ends to the fixed portions of the bearing 24 upon which the frame 18 is mounted and at its intermediate 110 portion is slightly spaced from a perforation passing transversely through the shank

of the frame 18. By this arrangement it will be seen that the said frame 18 has limited castered movement with relation to the bearing 24.

5 From the above description it is obvious that when the carrier is placed upon a supporting cable as indicated and is subjected to a sudden shove to move the same along the cable and as the shove is applied to that 10 end thereof opposite the end over which the wheel 20 is located that should there be a tendency to lift the forward end of the bucket or carrier then the wheel 20 may be permitted to remain at the same level that 15 is to say upon the upper surface of the cable 15 and is not compelled to follow the forward end of the carrier in its upward movement. Thus the possibility of detaching or 20 derailing the wheel 20 from the cable track 15 is reduced to a minimum for as soon as the push is delivered the forward end of the carrier will descend by gravity and the parts will assume their proper normal condition.

Inasmuch as the frame 18 is allowed to 25 have limited castor movement only there is sufficient movement on the part of the said frame to permit the wheel 20 to follow a curved cable track 15 without jumping from the same but at the same time the movement 30 of the frame 18 is not sufficient to permit the wheel 20 to swing laterally away from the cable or track 15 when the carrier is given a sudden push as indicated. By reason of the fact that the frame 16 is freely castered 35 it is at liberty to follow along the course or track of the cable 15.

The carrier herein shown and described may be used in connection with any suitable form of stop or depressor attached to the 40 cable 15 and as the carrier passes along this cable the power end of the lever 14 may be carried under such a depressor whereby the said lever is formed upon its fulcrum and the rod 9 is moved longitudinally. Such 45 movement on the part of the rod 19 disengages the end from the slot 4 in the periph-

ery of the disk 3 and the bucket 1 is free to turn laterally and assume a dumping position in a manner usually employed in devices of this character.

Having described my invention what I claim as new and desire to secure by Letters Patent is:

1. A carrier comprising a bucket and a bail, a supporting wheel located at one end of the bail, and being relatively fixed vertically with relation to the same and a supporting wheel located at the other end of the bail and being free for limited vertical movement with relation to the bail. 50 60

2. A carrier comprising a bucket and a bail, a caster wheel located at one end of the bail and being relatively fixed in a vertical direction with relation to the bail, a caster wheel located at the other end of the 65 bail and having limited vertical swinging movement with relation to the bail.

3. A carrier comprising a bucket and a bail, a caster wheel located at one end of the bail and being relatively fixed vertically 70 with relation to the same, a frame mounted for limited castered movement at the other end of the bail, an arm mounted for limited vertical swinging in the last said frame and a supporting wheel journaled for rotation in 75 the said arm.

4. A carrier comprising a bail, a bucket pivotally mounted in the bail, a disk attached to the bucket, and having in its periphery a slot, a pin located upon the outer 80 face of the disk and adapted to engage the side of the bail when the bucket assumes dumping position, and supporting wheels for the bail.

In testimony that I claim the foregoing 85 as my own, I have hereto affixed my signature in the presence of two witnesses.

CLEMENS B. WILLENBORG.
